UNITED STATES PATENT OFFICE.

HORATIO G. H. REED, OF MILWAUKEE, WISCONSIN.

FREIGHT-CAR-DOOR LOCK.

SPECIFICATION forming part of Letters Patent No. 276,283, dated April 24, 1883.

Application filed December 21, 1882. (No model.)

To all whom it may concern:

Be it known that I, HORATIO G. H. REED, of Milwaukee, in the county of Milwaukee, and in the State of Wisconsin, have invented certain new and useful Improvements in Locks for Freight-Car Doors; and I do hereby declare that the following is a full, clear, and exact description thereof.

My invention relates to the locking of freight-car doors, and will be fully described herein-after.

In the drawings, Figure 1 is a plan view of a portion of the side walls of a freight-car, and Fig. 2 is an inside view of the same.

15 A is a side and B is an end door of the car. a is an elbow-lug, secured near its upper edge to the side door, and C is a bifurcated dog, that is pivoted to the inside of the car, so that its arms c c' will project down in position to 20 engage with the lug a when the door A is moved back and forth.

The arm c of the dog C terminates in a pivoted finger, c², while the arm c' is connected by a rod, D, with one end of a spring-bar, D', the 25 other end of which is secured against the end of the car at d, and about midway between the ends of this spring I provide it with a pin, d', that projects through the end of the car above the doorway, and I make a mortise, b, in the 30 upper rear corner of the door to receive the pin when the door is closed. In the drawings I have shown both doors shut, and when this is the case the pin d' is held in the door B by the pressure of the lug a upon the arm c' of 35 the dog C, which, acting upon the rod D, tends to compress the spring D' against the end of the car; but, if the door A should be closed while the end door is open, the pin d' will be merely pressed against the plate b', in position 40 to take into the perforation b when the door is closed. This is made possible by the elasticity

of the bar D', which bends as the lug a presses the bar D toward its end of the car. When the door A is opened the lug a, striking the finger c² and crowding under and past it, will 45 turn the dog C, so as to cause its arm c' to draw upon the rod D and spring-bar D', thereby withdrawing the pin d' from the perforation in the door B; but as the door A is again shut the finger c² will yield and permit the lug a to 50 pass beyond it to the arm c'. I propose in this way to connect each side door with an end door, and thereby do away with any necessity for climbing over the freight in a car to lock or unlock the end doors.

With my device, as soon as the side doors are opened, the end doors become unlocked, and the closing of the side doors locks the end doors, if they are closed; but if they should be open when the side doors are closed it is 60 only necessary to close them and the pin d' will fly into place.

Having thus described my invention, what I claim as new, and desire to secure by Letters Patent, is—

1. The side door of the car, having a lug, a, in combination with a dog, C, the pin d', and connections, as set forth.

2. The combination, with an end and side door of a car, of the spring-bar and its pin, bar D, and dog C and lug a, as set forth.

3. The dog C, having arms c c' and finger c², in combination with doors A and B, pin d', and connections D D', as set forth.

In testimony that I claim the foregoing I 75 have hereunto set my hand, on this 4th day of December, 1882, in the presence of two witnesses.

HORATIO G. H. REED.
